UNITED STATES PATENT OFFICE.

JOHN HORNUNG, OF DRESDEN, OHIO.

RAILROAD-TIE.

No. 918,554.

Specification of Letters Patent. Patented April 20, 1909.

Application filed January 19, 1909. Serial No. 473,076.

To all whom it may concern:

Be it known that I, JOHN HORNUNG, a citizen of the United States, residing at Dresden, in the county of Muskingum and State of Ohio, have invented a certain new and useful Improvement in Railroad-Ties, of which the following is a specification.

The object of this invention is to provide a railroad tie of simple, cheap and durable construction, the body or main portion of which can be manufactured out of standard material that is readily obtainable in the open market, said tie being provided, as hereinafter set forth, with cushioning blocks 10 to receive the rails so as to lessen the noise and reduce the rigidity of the road.

The invention is embodied in the construction hereinafter particularly set forth and pointed out in the claims, the invention 20 not being confined in its embodiment to precisely the form of the parts shown.

In the accompanying drawings—Figure 1 is a side elevation of the tie, the rails thereon being shown in section. Fig. 2 is 25 a top plan view of the same. Fig. 3 is a partial section vertically on the line $x-x$, Fig. 2. Fig. 4 is a partial section horizontally on the line $y-y$, Fig. 3.

Like characters of reference in the several 30 views designate corresponding parts.

In said views the character 5 designates the tie body which consists of a piece of iron or steel I-beam of the proper length pressed or bent downward to extend outwardly at 35 its ends to form seats for cushioning blocks 6 of wood or other suitable cushioning material. The blocks 6 can each be beveled at its inner end as indicated by broken lines Fig. 1 to conform to the downwardly inclined surface presented at the bent portion 40 of the I-beam. But said blocks can be cut off square at both ends. The character 7 designates the rails, which at one side are secured to the wooden blocks by means of 45 the inner metallic clamping blocks 8 held down by nuts 9^a on bolts 9, the latter having their threaded ends extending upward through 50 holes in the tie body, the wooden block and the said metallic block 8, said block 55 gripping the inner base flange of the rail. At the outer side the rails are secured by means of metallic clamping blocks 10 held by nuts 11^a on bolts 11 having their threaded ends extending upward through 55 holes in the tie body, the wooden block and the said metallic block 10, the said block

gripping the outer base flange of the rail. The bolt holes in the tie body 5 are preferably elongated, as seen at 5^b in Fig. 4, and the shanks of the bolts where they engage said holes are preferably square to fit in said elongated holes so that, first, the rails can be shifted laterally to obtain the proper gage and allow for expansion and contraction, and, second, to permit the turning of 60 the nuts without turning the bolts.

The bolt holes in the cushioning blocks can be either circular and of a diameter to just receive the bolts, or they can be elongated like the holes in the tie body 5. If 70 they be made circular and the bolts fit closely in them the said block will of course be shifted with the bolts if they be shifted. If the bolt holes in the cushioning blocks be made circular, as stated, the block should 75 be made short enough to allow shifting inward if necessary.

The metallic blocks, as 10, can be made with fingers, as seen at 10^a, extending downward and lying against the sides of the tie 80 body to aid in locking them and the wooden blocks in place.

If desired, the lips of the tie body at the crown can be pressed down flat, and to save 85 material and allow tamping with a bar in ballasting, the web of the body can be cut out at its middle as seen at 5^a. The form of the tie body when suitably embedded prevents shifting of the tie laterally in the road bed.

The cushioning blocks are not necessarily 90 made of natural wood. They can be made of any suitable cushioning material, macerated wood fiber or papier mâché, for examples.

With my construction of tie body old 95 wooden ties can be saved and used by cutting them up into the smaller pieces adapting to form the cushioning blocks herein referred to.

What I claim and desire to secure by Letters Patent is:

1. A railroad tie, comprising, in combination, a tie body consisting of a piece of I-beam bent downward and outward at its 105 ends to form seats, and cushioning blocks in said seats with means for securing them therein.

2. A railroad tie, comprising, in combination, a tie body consisting of a piece of I-beam bent downward and outward at its 110 ends to form seats, cushioning blocks in said

seats, metallic blocks to engage the bases of the rails, and securing means engaging the tie body, the cushioning blocks, and the said metallic blocks.

- 5 3. A railroad tie, comprising, in combination, a tie body consisting of a piece of I-beam bent downward and outward at its ends to form seats, cushioning blocks in said seats, a metallic block to engage the base 10 of the rail having downwardly extending fingers to engage the tie body, and means for securing the said metallic block, the cushioning block and tie-body together.

4. A railroad tie, comprising, in combination, a tie-body consisting of a piece of I-beam bent downward and outward at its ends to form seats, rail-receiving cushioning blocks in said seats, means on said cushioning blocks to engage the rail and laterally adjustable bolts to secure the cushioning block, the rail engaging means and the tie-body together. 15 20

JOHN HORNUNG.
